UNITED STATES PATENT OFFICE.

JOHN C. BERGNER, OF LANSDOWNE, PENNSYLVANIA, ASSIGNOR TO THE BARBER ASPHALT COMPANY, OF PHILADELPHIA, PENNSYLVANIA, A CORPORATION OF WEST VIRGINIA.

DEVICE FOR FASTENING SHINGLES.

Application filed March 5, 1925. Serial No. 13,211.

My invention relates to devices useful in fastening shingles in place, more especially shingles lapped in the ordinary way as distinguished from those adapted to be laid diagonally.

The main object of my invention is to enable ordinary lap shingles to be fastened to the supporting structure of a roof with their exposed ends restrained from displacement against wind pressure.

How this desideratum may be obtained, together with other advantages, will be readily understood from the detailed description which follows of typical embodiments of my invention; while its scope will be as readily deductible from the appended claims.

In the drawings, Fig. I is a fragment of a roof with lapped shingles secured with fastening devices of my invention.

Fig. II is a view in perspective on a larger scale of the fastening devices shown in Fig. I; and

Fig. III is a similar view of a slightly modified form of my invention.

As shown to best advantage in Figs. II and III of the drawings, my improved shingle fastening device may be generally and briefly described as comprising securing means in the form of reversely angled or right and left hand prongs 1, 1, a shank comprehensively designated by the numeral 2, and offsets or projections 3—3 extending laterally from the end of said shank. Such a device may obviously be made in a number of different ways; but for convenience and economy of manufacture, I prefer to construct it of a single piece of wire sufficiently stout or heavy to serve the purpose for which the device is intended. The form of Fig. II may be produced by bending the wire to the configuration there shown, with the ends of the wires serving as the prongs 1, 1, turned downwardly from lateral extensions 4—4 of parallel bars 5—5 which constitute the shank 2 previously referred to; while the lateral offsets or projections 3—3 are afforded by forming the wire into a comparatively flat triangular loop 6. The bars 5—5 may be disposed in slight separation to serve as gauges in determining the lateral spacing of the shingles as will become apparent from further description. The ends of the prongs 1, 1 are reduced to the

form of points so that they may be readily driven by a hammer in securing the shingles; while the loop 6 is preferably raised or offset somewhat above the plane of the shank 2 to allow for the thickness of the shingle material. The latter of these provisions may be instituted by joggling as indicated at 7—7 incidentally to the manufacture of the device.

The modification of Fig. III differs from the form just described in detail only, in that the two bars of the shank 2 are twisted together as suggested in the illustration, for greater rigidity of the fastener as a whole.

In constructing a roof with the aid of fastening devices of my invention, the procedure is as follows:

The shingles indicated by the letter "S" in Fig. I are laid in the usual superposed lapped relation, and, either incidentally to the handling of the individual shingles, or after a complete course is laid, the fastening devices are allocated so that their shanks 2 are aligned with the vertical medial of the shingles; prongs 1, 1, may be driven approximately centrally through those portions of the shingles "S" which are to be subsequently overlapped. A succeeding course is then superposed upon the first in the desired lapped relation, secured in the same manner as before, and the exposed ends of adjacent pairs incidentally engaged for retention against displacement, beneath the lateral projections 3—3 at the lower ends of the shanks 2, 2 of the fastening devices of the subjacent course. It will at once be obvious that as a result of the offsetting or joggling of the loops 6 relative to the shanks 2, the latter are permitted to lie, throughout their length, directly against the shingle surfaces, thereby enhancing the securing effect of the device.

Although I have herein shown and described my invention in connection with the laying individual shingles "S", they may be used with equal advantages in securing shingles of strip form as long as their position with respect to the shingle tips is so ordered that they function in the capacity explained.

Having thus described my invention, I claim:

1. A fastening device for shingles fabricated from a single piece of wire to provide reversely angled prongs for penetrat-

- ing that portion of the shingle normally overlapped and to secure the same on a supporting structure, a shank adapted to repose in the interval of a pair of adjacent shingles of a superposed course, and an offset terminal loop affording opposed projections functional to grip the side edges of said adjoining shingles and restrain them against displacement.
- 10 2. A fastening device for shingles fabricated from a single piece of wire to provide reversely angled prongs for penetrating that portion of the shingle normally overlapped and to secure the same on a supporting structure, a downwardly directed shank adapted to repose in the interval between a pair of adjacent shingles of a superposed course, and an offset terminal loop affording lateral projections functional to grip the side edges of said adjoining shingles and restrain them against displacement.
- 15 3. A fastening device for shingles fabricated from a single piece of wire to provide reversely angled prongs for penetrating that portion of the shingle normally overlapped and to secure the same on a supporting structure, a downwardly directed shank adapted to repose in the interval between a pair of adjacent shingles of a superposed course, and an offset terminal loop affording lateral projections functional to grip the side edges of said adjoining shingles and restrain them against displacement.
- 20 4. As a new article of manufacture a fastening device for shingles fabricated from a single piece of wire to provide paralleled shank members having reversely angled attaching prongs at one end and an offset triangular loop affording lateral gripping portions at the other end.
- 25 5. As a new article of manufacture a fastening device for shingles fabricated from a single piece of wire with paralleled portions twisted to provide a rigid shank having reversely angled attaching prongs at one end and a triangular expanded offset affording opposed gripping projections at the other end.

In testimony whereof, I have hereunto signed my name at Philadelphia, Pennsylvania, this 2nd day of March, 1925.

JOHN C. BERGNER.
